Fig. 3

Fig.4

Fig.5

FIG. 1 is a front elevational view of a desk showing my new design, and

FIG. 2 is an end elevational view thereof as viewed from the left of FIG. 1.

FIG. 3 is a perspective view of my desk showing my new design;

FIG. 4 is a perspective view similar to that of FIG. 3 but with the auxiliary desk opened in one position; and

FIG. 5 is a similar view, with the auxiliary desk extended in another position.

The design is characterized by the auxiliary table which supports one end of the desk and is pivoted thereto at one side edge thereof by a center rod which permits the auxiliary table to be pivoted 360°. The back of the desk is conventionally plain.

I claim:

The ornamental design for a desk, substantially as shown and described.
